WELL REAMING APPARATUS

William R. Barbour, Atlanta, Ga.

Application November 25, 1944, Serial No. 565,121

13 Claims. (Cl. 255—76)

1

Generically this invention relates to reaming devices, but it more particularly is directed to a rotary device or apparatus for reaming out to a larger diameter any desired portion of oil wells and the like.

One of the principal objects of this invention is the provision of a device of this character attachable to a string of drill pipe, controllable from the surface of the ground, and comprising an improved hollow reamer shaft, and expansible reamer arm construction and shoe assembly associated with said shaft operable to effect reaming out of a chamber or enlarging any portion of the well bore and permitting a fluid circulation through the device including the shoe to the bottom of the well for clean out purposes and cooling of the reamer arms.

Another object of this invention is the provision of an upper collar structure having detachable connection with the end of the drill pipe and adapted to be slidably mounted on the upper end of the reamer shaft and to impart rotary motion thereto and to the attached reamer arms and thrust rods.

A further important object of this invention is the provision of a reamer arm assembly adapted to be mounted on a reamer shaft, and comprising a plurality of articulated sets of reamer arms attached at one end to an upper or control collar and at the other end to a lower slidable collar and movable into overlying parallelism with the reamer shaft and to expanded or reaming position, and means associated with said collars adapted to transmit force and downward movement from the upper to the lower collar and arms when expanded or moving in reaming direction, said arms being automatically foldable by the upward movement of said upper collar.

Another important object of this invention is the provision of a hollow reamer shaft adapted to be slidable through a collar attached to the end of a drill pipe and having means adapted to prevent its dropping out of or becoming detached from said collar, a plurality of sets of expansible reamer arms associated with said shaft with their upper ends attached to said collar and their lower ends attached to a lower slidable collar mounted on said shaft, means in connection with said shaft for preventing the lower collar from sliding down said reamer shaft until the reamer arms have substantially reached their expanded position, and means in connection with said shaft to permit the folding of the reamer arms into overlying parallelism therewith at any desired point throughout its length.

2

A further important object of this invention is the provision of an articulated reamer arm structure mounted on a reamer shaft and adapted to be inserted in a drilled well in folded parallelism with the shaft, and means in connection with said shaft and coating with said arm structure to initially start the outward movement of said arms in expanding direction.

A still further important object of this invention is the provision of a shoe structure or assembly attachable to the lower end of the reamer shaft adapted to rest on the bottom of the well and support the shaft and associated reaming mechanism on a thrust bearing, the construction being such as to present a long bearing surface axially of the shaft tending to prevent wobbling of the shaft and to stabilize the supporting base, and the formation of the foot structure adapted to prevent movement and sinking of the base, thereby insuring the flow of the circulating fluid through the shoe to the bottom of the well.

With these and other objects in view, which will become apparent as the description proceeds, the invention resides in the construction, combination and arrangement of parts, hereinafter more fully described and claimed, in which like characters of reference indicate like parts throughout the several figures, of which:

Fig. 1 is a view in elevation with the reamer arms in closed position.

Fig. 2 is an elevation similar to Fig. 1 with the arms in expanded position.

Fig. 3 is a sectional view with the arms closed and in elevation.

Fig. 4 is a view similar to Fig. 3 with the arms expanded and in fragmentary elevation.

Fig. 5 is a fragmentary sectional view showing the ball and cams in arm opening position.

Fig. 6 is a fragmentary sectional view showing the lower arm cams in the cam receiving recesses.

Fig. 7 is a cross section on the line 7—7 of Fig. 3 showing the cam retaining pins in elevation.

Fig. 8 shows the upper collar partly in section, a portion of the connected drill pipe in section and connected parts in elevation.

Fig. 9 is a similar view to Fig. 8 in elevation with the upper collar partly in section.

Fig. 10 is a fragmentary longitudinal sectional view with the upper reamer arms in elevation.

Fig. 11 is a cross section on the line 11—11 of Fig. 10.

Fig. 12 is a cross section on the line 12—12 of Fig. 8.

Fig. 13 is a cross section on the line 13—13 of Fig. 8.

Fig. 14 is a longitudinal section of the shoe structure and portion of the reamer shaft.

Fig. 15 is a cross section on the line 15—15 of Fig. 14.

Fig. 16 is a sectional view of a portion of an oil well showing the reaming device in operative position therein.

Fig. 17 is an elevation of a modified form of reamer arm construction.

The devices of this character with which I am familiar have proven deficient in presenting complex structures, expensive to produce, difficult to readily position at any desired level, and in other ways unsatisfactory, and it was to overcome such disadvantages by providing a flexible device comprising an upper collar attachable to a string of drill pipe adapted to carry and control the articulated reamer arms, and to impart rotary motion to the hollow reamer shaft slidably connected therewith, said shaft carrying a fluid and ball controlled cam mechanism adapted to initially start the expanding movement of the reamer arms, a slidable lower collar on said shaft connected to the ends of the lower reamer arms, means carried by said shaft coacting with the cam means carried by the lower ends of said lower arms to hold the lower collar against downward movement until said arms have substantially reached their limit of expansion, and a compound shoe structure adapted to rest on the bottom of the well and to support said rotatable shaft and reaming assembly, said shoe including a supporting thrust bearing and axial bearing surface for said shaft and means for directing the fluid flow from said shaft therethrough to the bottom of the well, that I designed the device forming the subject matter of this invention.

In the illustrated embodiment characterizing this invention there is shown a drill pipe 1, externally threaded at its lower end as at 2, and an upper collar 3 formed with a threaded countersunk opening 4 adapted to engage and receive said threaded end of a pipe 1. Said collar is provided in the present instance with a vertical opening 5 square in cross-section adapted to fit the hollow square reamer shaft 6 slidably extending therethrough. It is obvious that the shaft and opening may be of any desired shape adapted to impart the rotary movement of collar 3 to said shaft. Threadedly mounted on the upper end of shaft 6 is a nut 7 adapted to coact with the shoulder 8 to prevent disengagement of the shaft from said collar as will be well understood. The upper surfaces of the nut and shaft are concaved as at 7' to direct a ball 9 from the drill pipe 1 to the hollow bore 10 of said shaft for a purpose hereinafter more fully explained.

Integrally or otherwise formed on the lower end of collar 3 are the equispaced bifurcated lugs 11 positioned over the respective sides of the shaft. Adapted for overlying relation with respect to each of the four surfaces of said reamer shaft 6 are respective sets of reamer arms A comprising upper arm sections 12 hingedly connected at their upper ends to lugs 11 by pins 13, and hingedly connected at their lower ends to the upper ends of the lower reamer arms or sections 14 by pins 15, the lower ends of arm sections 14 being connected by pins 16 to lugs 17 projecting from the upper edge of the slidable collar 18, in a manner similar to lugs 11.

The lower ends of the arm sections 14 are formed with cams 19 adapted to seat in the complementary cam-stop recesses 20 formed in the respective surfaces of shaft 6, and which prevents

downward slidable movement of collar 18 (Fig. 3) during lowering of the device in the well D and until arms 14 have moved to expanded position (Fig. 4). Just below recesses 20 and in alignment therewith, said shaft 6 is formed with the recesses 21, ending at or near the lower end of the shaft and which correspond in depth and width to the recesses 20, and which are adapted to receive the cams 19 and permit closing of the arms A at any point desired when the lower ends of arms 14 are below recesses 20. Each of the respective arm sections 12 and 14 is formed at its forward edge with a cutting edge or cutting teeth 14'. The respective reaming arm sections 12 are longer than the reaming or cutting sections 14 so that when in open or expanded position the outer ends of the latter at connections 15 will be elevated somewhat with respect to their inner end connections 16 (Figs. 2 and 16) to effect the desired cutting or reaming angle, and distribution of the forces applied to the reaming assembly B during the reaming operation.

Just below the hinged connection 15 of the arm sections 12 and 14, and formed in the respective 25 opposed surfaces of shaft 6, are the openings 22 terminating in the downwardly extending recesses 23.

Mounted in the openings 22 and with their rounded and beveled edges 22' converging into 30 meeting engagement centrally of the bore 10 (Fig. 7) are the cam members 25 normally seating in the recesses 23 flush with the surface of said shaft 6. Extending through said shaft 6, spaced from the opposed surfaces of the shaft and in 35 parallelism therewith, are the bores 26, and similarly extending through the remaining opposed surfaces and intersecting bores 26 at right angles thereto are the similar bores 27. Inserted in bores 26 and through the cams 24 are the short pins 28 40 adapted when operatively positioned not to interrupt the bores 27, and inserted in bores 27 and through the remaining cams 24 are the long pins 29, the ends of which are flush with the opposite surfaces of shaft 6 (Fig. 3). As clearly 45 shown in Figs. 3 and 7, when the reamer arms 12 and 14 are in closed position the cams 24 are likewise in closed position within bore 10. If desired, instead of the bores 26 and 27, the surfaces of 50 the reamer shaft may be slotted and the cam pins 28 and 29 welded or otherwise secured therein.

Sometimes when pressure is applied to arms 12 and 14 by collar 3, by reason of said arms being on dead center at joint 15 or otherwise, they 55 fail to move in expanding or opening direction, and in order to insure positive action in such regard the cam 24 arrangement has been provided so that ball 9 (Fig. 5) acting on surfaces 22' under the pressure of the fluid passing through bore 10, is forced between cams 24 elevating cam arms 25 and expanding said arms 12 and 14 at joint 15, thereby starting the outward and expanding movement of said arms in reaming direction, as will hereinafter be more fully described.

65 The bottom surface of upper collar 3 is formed intermediate adjacent lugs 11 and at the four corners of opening 5 or shaft 6 (Fig. 13) with the threaded openings 30, each adapted to receive the reduced threaded end 31 of a thrust rod 32. 70 Each of said rods 32 is formed with a shoulder 33 and a reduced guide rod portion 34, of a flat or any desired shape in cross section, adapted to slidably extend through a similarly shaped opening 35 in the lower collar 18 (Figs. 1 and 2). 75 These rods 32 not only tend to further stabilize

the reaming assembly B and by the engagement of shoulders 33 with the surface of collar 18 limit the expansive movement of the arms when they have reached their predetermined cutting positions, but also to establish a positive drive from upper collar 3 to the slidable lower collar 18 and to said arms.

The reamer shaft 6 is preferably constructed at its lower end with an enlarged portion 36 having a reduced tapered threaded end portion 37 adapted for detachable connection with a shoe assembly C.

The shoe assembly C is adapted, as will directly more fully appear, to rest on the bottom of a well and support the weight of the reamer construction, and comprises a complementally formed and threaded collar or socket member 38 adapted to receive the tapered end 37 of shaft 6. Said member 38 is formed with a bore 10' forming when positioned a continuation of bore 10 and which extends to the closed end 39 of the depending cylindrical member 40 formed integrally with said collar 38, and which adjacent its closed end is provided with an annular series of outlet openings 41. A socket or cup-like member 42 is dimensioned to receive the member 38 and is formed with a reduced externally threaded portion 43 having a bore 44, of slightly greater diameter than the cylindrical portion 40 extending therethrough, to provide the coil or lubricating space 45.

Seating in said socket member 42 is a thrust ball or roller bearing 46 on which is supported collar member 38. The upper end of socket 42 is formed with the threaded countersunk portion 47 in which is threadedly engaged the packing ring 48, surrounding collar 38, and adapted to compressingly engage the packing 49. A base member 50 is formed at its upper end with a threaded socket 51 adapted to threadedly receive the threaded end 43 of member 42, and is formed at its lower end with a plurality of equi-spaced feet members 52 which extend below the bottom element 39 and are adapted to be supported on the bottom of the well. Base member 50 is provided with a central bore 53 adapted to register with and form a continuation of bore 44 and oil space 45. The bottom of said base member is threadedly countersunk surrounding the bore 53 as at 54 to receive the packing ring 55 mounted on the lower end of the cylindrical portion 40 of member 38 for engagement with packing 49, similar to ring 48. It will thus be noted that such shoe construction effects a long bearing surface, extending from packing ring 48 to the packing ring 55, for the reamer shaft 6 supported on the thrust bearings 46 and carrying the reamer structure. Also the construction of the shoe and base portion is such as not only to provide a stable supporting structure but to prevent its bogging down and at the same time effect fluid circulation through the shoe structure to the bottom of the well and thereby maintain the well at all times clear of the material reaching the bottom from the reaming operation.

It should be noted here that while the threaded reamer end 37 of shaft 6 and the complementally threaded socket structure of collar 38 of the shoe assembly C (Fig. 14) in the present instance, differs slightly from the corresponding construction of the drill pipe 1 and collar 3 (Fig. 8), it is to be understood that it may be similarly constructed and interchangeable, so that a length or lengths of drill pipe may be attached to the shaft portion 37 or insertable intermediate said

portion and collar 38, depending upon the depth of the well and the location of the oil bearing stratum to be reamed with respect to the shoe assembly at the bottom of the well.

In Fig. 17 is illustrated a modified form of reamer arm structure, similar in principle to the form hereinbefore described, but instead of the two hinged arm structure A, a three articulated or hinged arm structure A' is employed. This form, while not limited to, is especially applicable to chambers already reamed, the pores of the walls of which have become plugged with hardened oil and the like, and in such cases where no great depth of stratum has to be removed, it will operate more quickly than the form heretofore described. In Fig. 17 there is shown a drill pipe 1, the upper collar 3', shaft 6', sliding collar 18', and shoe structure C, which are similar to the parts 3, 6, 18, and C heretofore described. However, in this instance each of the articulated or hinged arms A' comprise an upper arm section 56 with its upper end suitably hinged to lug 11', and a similar lower section 57 with its lower end suitably hinged as at 58 to the shaft 6', in the present instance, adjacent to shoe C, but which may be at any desired point spaced therefrom. These arms are connected by an intermediate arm section 59 hingedly connected as at 60 to arm 56, and as at 61 to arm 57, the arm 59 at all times extending in parallelism with shaft 6' whether in folded or overlying position with respect to said shaft or in expanded position.

It will be observed that in the present instance there are four sets of these arms A', corresponding to the sets A heretofore described, but for brevity of description there are shown only two opposed sets. Each of the arms 59 centrally of their length are formed with a pair of ears 62, between which are hinged the outward ends of the upper and lower brace rods 63 and 64, respectively. The upper end of rod 63 is suitably and hingedly connected to a lug 65 suitably formed on or attached to the end surface of collar 18', and the lower end of brace rod 64 is hingedly connected by pin 66 to collar 67 suitably anchored or attached to shaft 6'. Suitably connected at their upper ends to collar 3', and at their lower ends to collar 18', are the thrust rods 32' which operate similarly to rods 32 except they are also connected to collar 18' and not only transmit force from collar 3' to collar 18', and outwardly to arms 59 through the braces 63 and 64 and shaft 6', during the reaming operation, but effect synchronous movement of the collar 18' with respect to collar 3' in either direction. The upward movement of collar 3' on shaft 6' effects moving the arms and braces into folded and overlying relation with respect to shaft 6', since arms 57 and braces 64 are hingedly secured to shaft 6', and in such folded position this form of reamer assembly B' is ready for insertion into or removal from a well, the operation in this regard being similar to assembly B. The forward outer edges of these arms are formed with cutting edges 65 similar to arms 14, or as desired. The cam mechanism 24 is also applicable to this form.

Fig. 16 diagrammatically illustrates a well D drilled in ground 68 and with the form illustrated in Figs. 1 and 2 in operative position in process 70 of forming or reaming the chamber E. When the arms A of the reaming assembly B are in closed position as shown in Fig. 1, it is evident that the apparatus can be inserted in the well D with the shoe assembly C resting on the bottom of the well, and when rotary movement has been im-

parted to the device, chamber E will be formed. While the operation of the device would seem to be clear from the above description, it might be well to further state that when the device is in closed position, as shown in Fig. 1, it may be inserted in a drilled well, and as rotary movement is suitably applied to drill pipe 1, it will be transmitted through collar 3 to reamer shaft 6, and by the weight of the equipment or as force is applied to said collar it will tend to slide downwardly on said shaft, and as the cams 19 are positioned in cam recesses 20 the lower collar is prevented from moving downwardly. Therefore, the arms A at joint 15 will move outwardly in expanding direction and in reaming engagement with the wall of the well until they have substantially reached their expansive limit, as shown in Fig. 4, and at which time the cams 19 have moved out of the recesses 20, so that as force is applied to collar 3, collar 18 and arms 14 are moved down in reaming direction, since force is applied directly from collar 3 to arms 12 and to collar 18 through thrust rods 32 said collar 18 and arms are free to move downwardly in reaming direction as shown in Fig. 16. At the same time the reaming structure is supported by the shoe structure C resting on the bottom of the well, and its formation, including the cleats or feet 52 and bottom 39 tend to prevent it from sinking into said bottom, thereby permitting the fluid stream being pumped through said shaft 6 and the shoe structure to discharge through lateral openings 41 and to carry the reamed material that has reached the bottom of the well upwardly between the shaft 6 and the wall of the well, and from chamber 5, out of the top of the well. This not only maintains the well at all times clean, but the material content of the fluid is entrained with the upward flow as it passes through chamber E by the rotating action of the arms causing an outward motion of the circulating fluid against the walls of the chamber by the whirling movement set up in the fluid which not only effects a continuous passage of the fluid from the well and insures the efficient removal of waste material, but lubricates and maintains the cutting portions of the reamer arms cool.

In initially starting the device, the arms 12 and 14 may not move outwardly by reason of being on dead center or otherwise, and to overcome this difficulty and to insure positive action and immediate breaking of the joint irrespective of the position of the arms, a steel ball 9 is inserted in the drill and fluid supply pipe above the cams 24, and the fluid passing through bore 10 forces the ball against the cam surfaces 22' which actuates the cams to open position permitting the ball to pass through, and at the same time elevating arms 25 into engagement with arms 14, thereby breaking the joint and starting the outward movement of the arms as shown in Fig. 5. Also, I might add, that after collar 18 has moved below recesses 20, the folding of the arms A may be effected at any point desired since cams 19 are free to move into recesses 21.

To remove the device from the well, if the cams 19 are not below recesses 20, upward movement of the drill pipe and collar 3 fold the arms into parallelism with the shaft, as in the first instance, and head 7 engaging shoulder 8, pulls the entire device upwardly. However, should the cams 19 be below recesses 20, the upward movement of collar 3 will fold the arms, and when cams 19 have reached the upper ends of recesses 21, being unable to pass beyond said ends, the shaft and con-

nected parts will be moved upward as above described.

It is to be noted that the ball 9, after passing through cams 24, passes with the fluid to the bottom of the shoe and rests on bottom 39 below openings 40 and, therefore, may be recovered for future use when the apparatus has been withdrawn from the well.

From the above description it will be apparent that I have designed an oil well reaming or cutting device which has for its principal purpose the reaming out to a larger diameter of such portions of oil wells as pass through oil bearing strata, in order to increase the exposed surfaces of such strata and thus induce a larger flow of oil. The entire device is mounted on the reamer shaft 6 comprising the reamer assembly B including the upper collar 3, lower slidable collar 18, the sets of expandable reamer arms A, and the shoe assembly C. The construction of the arms and collar connections is such that while they have free foldable and expandable vertical movement they are prevented from horizontal movement independently of the movement of collar 3. There is means carried by its upper end for preventing shaft 6, slidable through said collar 3 and adapted to extend within the drill pipe 1, from separation from said collar which is adapted for detachable connection with drill pipe 1. Said device is compact in form, and the weight of the parts below collar 3 automatically effects folding of the arms with respect to the shaft during the lowering of the device into the well and its withdrawal therefrom, said device being versatile in its adaptive use under varying operating conditions, and especially by reason of the arm assembly B^a being interchangeable with assembly B without necessitating material structural alterations, said device being simple in construction, manufacturable at a reasonable cost, and efficient for the purposes intended.

Although in practice I have found that the form of the invention illustrated in the accompanying drawings and referred to in the above description as the preferred embodiment, is the most efficient and practical, yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A well reaming apparatus comprising a rotary drive member, a reamer shaft, a reaming assembly slidably mounted on and adapted to rotate with said shaft comprising upper and lower collars, an articulated cutting arm hinged intermediate its length and having its ends attached, respectively, to the upper and lower collars, said arm having collapsed and expanded positions, co-acting means between the lower end of the arm and shaft to prevent downward movement of said assembly, said means including a cam element on said arm normally projecting into a seat formed in said shaft releasable when said arm has substantially reached its predetermined expanded position, and means including a stationary member for rotatably supporting the lower end of said shaft.

2. A reaming apparatus comprising a rotary drive member, a reamer shaft, a reaming assembly

connected to said drive member and slidably mounted on and adapted to effect rotation of said shaft and comprising upper and lower collars, collapsible reaming arms having their ends attached, respectively, to the upper and lower collars, co-acting means between the lower ends of the arms and shaft to prevent the downward movement of said lower collar during the expanding movement of said arms but releasable when said arms have substantially reached their expanded positions, said means including cams on said arms normally seating in recesses in said shaft, and means including a stationary member for rotatably supporting the lower end of said shaft.

3. A well reaming apparatus comprising a rotary fluid supply drill pipe, a hollow reamer shaft, a reaming assembly slidably mounted on and having rotary drive connection with said shaft and including upper and lower collars, articulated expandible arms operable by the upward movement of said upper collar into parallelism with said shaft and having their ends attached, respectively, to the upper and lower collars, means during the downward movement of said upper collar for maintaining the lower collar fixed with respect to said shaft until the arms have substantially reached their expanded positions, said means including cams on said arms normally seating in recesses in said shaft, means including a stationary member for rotatably supporting the lower end of said shaft, said stationary member having a central bore forming a continuation of the bore of said shaft whereby a fluid flow is directed through and below said device and stationary member to the bottom of the well.

4. A well reaming apparatus comprising a rotary fluid supply drill pipe, a hollow reamer shaft in communication with said pipe, a reaming assembly slidably mounted on and having rotary drive connection with said shaft and including upper and lower collars, articulated cutting arms having expanded and collapsed positions attached to said collars, said upper collar being attached to said drill pipe, means including a stationary member for rotatably supporting the lower end of said shaft, said means having a central bore forming a continuation of the bore of said shaft whereby a fluid flow is directed through said device and stationary member to the bottom of the well, means in connection with said shaft normally interrupting the bore thereof and means operable through the bore for operating said interrupting means to start the initial outward movement of the arms in expanding direction.

5. A reaming apparatus comprising a rotary drill pipe and a reaming mechanism operated by said drill pipe, said mechanism including a reamer shaft and a reaming arm assembly slidably mounted on said shaft comprising a plurality of articulated reaming arms and upper and lower reamer arm carrying collars, the upper collar being secured to said drill pipe, said arms by the upward movement of said upper collar being movable to and normally extending in closed substantial parallelism with said shaft but expandable to reaming position by the downward movement of said upper collar, means for maintaining said lower collar against slidable movement until the arms have moved to expanded position, said means including cams formed on said arms normally seating in recesses in said shaft, means for limiting the meeting movement of said collars and adapted to transmit force direct from the upper to the lower collar when

force is applied to said upper collar in reaming direction, and means for rotatably supporting the lower end of said reamer shaft.

6. A reaming apparatus comprising a rotary drive member, a hollow reamer shaft, a reaming arm assembly mounted on said shaft having connection with said drive member and including an articulated reaming arm normally extending in overlying parallelism with said shaft and operable into said position by said drive member and also by said drive member expandible to reaming position, means for starting the initial outward movement of said arm in expanding direction extending within said shaft, and means rotatably supporting the lower end of said shaft.

7. A reaming apparatus comprising a rotary drive member, a bored reamer shaft, a reaming arm assembly mounted on said shaft having connection with said drive member and including an articulated reaming arm movable into overlying parallelism with said shaft and expandible to reaming position, by the upward and downward movement, respectively, of said drive member means in connection with said shaft and co-acting with said arm to effect the initial outward movement of said arm in expanding direction, said means including displaceable elements extending into the bore of said shaft and means operable through said bore for displacing said elements, and means rotatably supporting the lower end of said shaft.

8. A reaming apparatus comprising a rotary drive member, a hollow reamer shaft through which a fluid stream is adapted to flow, a reaming arm assembly mounted on said shaft having connection with said rotary drive member and including reaming arms operable by the upward movement of said member into overlying parallelism with said shaft and expandible to reaming position by the movement of said member in downward direction, displaceable means in connection with said shaft co-acting with said arms and means operable through the bore of the shaft for displacing said means to effect starting of the initial outward movement of said arms in expanding direction, and means rotatably supporting the lower end of said shaft.

9. A reaming apparatus comprising a rotary driving member, a reamer shaft, a reaming assembly slidably mounted on said shaft and rotatable therewith including upper and lower collars, a plurality of reaming arms connected to said upper collar and at their lower ends to said lower collar, said arms comprising upper and lower hinged connected reaming sections, said arms being operable into overlying parallelism with respect to said shaft by the upward movement of said upper collar, but expandible to open reaming position by the downward movement of said upper collar, cam means carried by the lower ends of the lower arm sections co-acting with cut out seats formed in said shaft to maintain the lower collar fixed but releasable to permit downward movement of said collar when said arms have substantially reached their expanded position, and means for rotatably supporting the lower end of said shaft, said upper collar being connected to and operated by said rotary driving member and means in connection with said shaft for initiating and expanding movement of said reaming arms.

10. A reaming apparatus comprising a rotary driving member, a reamer shaft, a reaming mechanism connected to said rotary member and slidably mounted on said shaft and rotatable there-

with including upper and lower collars connected by a plurality of expandible reamer arms, said arms being operable by the upward movement of said upper collar into overlying parallelism with respect to said shaft, but expandible to reaming position by the downward movement of said upper collar, cam means associated with said arms and adapted to seat in recesses formed in said shaft to maintain the lower collar fixed during the expanding movement of said arms, said cam means being displaceable to permit movement of said collar with respect to said shaft when said arms are in expanded position, and additional recesses in said shaft adapted to co-act with said cams, when said lower collar has moved below said first mentioned recesses, to permit collapsing of the arms at any desired point with respect to said shaft, and means for rotatably supporting the lower end of the shaft.

11. A reaming apparatus comprising a rotary driving member, a reaming shaft, a reaming mechanism mounted on said shaft and rotatable therewith, comprising a pair of collars slidable on said shaft, including an articulated reamer arm associated with said shaft and attached to and controlled by the upper collar, said upper collar connected to and controlled by said rotary member, said arm being operable into overlying parallelism with respect to said shaft and expandible to open and reaming position by the upward and downward movement, respectively, of said upper collar, said arm comprising upper, lower, and intermediate hingedly connected sections, and means for rotatably supporting the lower end of said shaft.

12. A reaming apparatus comprising a rotary driving member, a reamer shaft, a reaming mechanism mounted on said shaft and rotatable therewith including upper and lower slidable collars, rods interconnecting the collars adapted to transmit force from the upper to the lower collar and to effect their synchronous movement, said mechanism including a plurality of reaming arms hingedly associated with said shaft and collars, each arm comprising upper, lower, and intermediate hingedly connected sections, and collapsible brace means between the shaft and said intermediate sections, said arms and brace means being operable into overlying parallelism with respect to said shaft by the upward movement of

said upper collar and expandible to open position by the downward movement of said upper collar, said upper collar being connected to and operated by said rotary driving member, and means for rotatably supporting the lower end of said shaft.

13. In combination with a rotary drill pipe, a bored reamer shaft, a reaming arm assembly slidably mounted on said shaft and including upper and lower collars, a plurality of reaming arms attached to said collars, said arms being operable into overlying parallelism with respect to said shaft by the upward movement of said upper collar and expandible to open position by the downward movement of the upper collar, means on said shaft co-acting with cams in connection with said arms and normally seating in recesses in said shaft to maintain said lower collar stationary during the expanding movement of said arms but releasable to permit downward movement thereof when said arms have substantially reached their expanded position, additional recesses in said shaft co-acting with said cams to permit folding of said arms at any desired point on said shaft, means carried by said shaft and co-acting with said arms operable to start the initial outward movement of the arms in expanding direction, and a shoe assembly comprising a stationary base bearing member, a member attached to the lower end of said shaft seating on said bearing member, rotatably supporting said shaft and constituting a journal bearing projecting longitudinally from said shaft through said base.

WILLIAM R. BARBOUR.
